UNITED STATES PATENT OFFICE.

JOHN W. CORNELIUS, OF SALINA, KANSAS, ASSIGNOR TO THE SHELLABARGER MILLS & ELEVATOR COMPANY, OF SALINA, KANSAS, A CORPORATION OF KANSAS.

APPARATUS FOR FEEDING FINELY-DIVIDED MATERIAL.

Application filed December 12, 1924. Serial No. 755,476.

This invention relates generally to a device for feeding finely divided solid material.

A general object of the invention is to provide a device of the general type referred to by which a stream of material is delivered at an accurately measured, uniform rate in response to a constantly maintained, unvarying pressure.

The invention includes a hollow casing 10 into which extends a rotatable shaft provided with material-moving blades or flights normally disposed in a helical relation to the axis of rotation of the shaft. The helically disposed blades are mounted at their leading or forward ends only on radially extending posts seated in the shaft. The trailing or rearward ends of the blades are free and, being formed of spring sheet metal, will yield under a maximum resistance and take 20 positions lying in planes perpendicular to the shaft whereupon no further movement of the material longitudinally of the shaft will occur until the pressure has decreased and the blades have sprung back again to 25 helical operating positions.

At the end of the casing toward which the material is fed by the blades a closure plate is provided with a discharge slit extending in a radial direction and provided with a 30 flanking knife edge extending inwardly to engage the forward end of the mass of material in the casing in a manner similar to the cutting bit edge of a carpenter's plane. A device for rotating the mass of material 35 adjacent the plate in order to cause a shaving or ribbon of material to be cut from the mass and diverted through the slit, is carried by the rotatable shaft.

Other features of the invention include a 40 gate member for adjusting the length of the discharge slit to thereby vary the width of the ribbon of material being fed therethrough. Means are also provided for agitating the material in a supply hopper 45 mounted on the casing to prevent jamming or blocking of the material therein.

With the construction described a stream of material of predetermined volume is fed through the discharge opening at an unvarying rate and representing only a small proportion of the capacity of the material-moving blades on the shaft. The uniform feed through the discharge opening is accomplished by the constant pressure that is maintained in the discharge end of the casing by

the resiliently yielding action of the material-moving blades.

In the drawings, in which a preferred embodiment of the invention has been selected for illustration,

Figure 1 is a perspective view of a mixing device embodying the invention.

Figure 2 is a view in vertical longitudinal section of the device shown in Figure 1.

Figure 3 is an end view of a set of stirring 65 blades forming part of the invention.

Figure 4 is an end view of a stirring member forming part of the device shown in Figure 1.

Figure 5 is a view in end elevation of an 70 agitating and feeding member forming part of the device.

Figure 6 is a view of an end plate provided with a discharge opening used in connection with the device.

75

Referring to the drawings for a more detailed description of the invention, a feeding device is shown which includes a body or casing 10 provided with a receiving hopper 11 and mounted on feet or standards 12 80 adapted to be attached to a suitable support. One end of the casing 10 is provided with a closure cap 13 having screw-threaded relation with the end of the casing and provided at its central portion with an elongated bearing sleeve 14 in which an operating shaft 15 is journaled.

85

The shaft 15 extends into the body of the casing 10 and is provided with a plurality of sets of material-moving blades 16 each 90 of which is mounted at one end on a radially extending post 17 seated in the shaft 15. The blades 16 are set at slight angular positions so as to form what is in effect a helical screw of low pitch so that material engaged 95 by the blades is given a progressing or traversing action through the casing 10 from the end of the cap 13 to the other end thereof.

In order to prevent clogging and to maintain a constant feed of material supplied to the hopper 11 into the body or casing 10, a set of stirring arms or fingers 18 is provided which is mounted on a rock shaft 19 journaled at its ends as at 20 in bearing 105 plates 21 mounted on the casing 10 at the rear and forward faces of the hopper 11. The rock shaft 19 is provided with a pair of downwardly extending actuating arms 22 which take positions on both sides of 110

the main operating shaft 15 as is shown in Figure 5 of the drawing so that a lug 23 carried by the shaft 15 engages the arms 22 in alternation to thereby rock the shaft 19 and thereby move the agitating arms 18 from side to side in the mass of material contained in the hopper 11. This agitating action prevents the clogging of material in the hopper and causes it to feed downwardly without interruption into the casing 10 where it is engaged by the material-moving blades 16 carried by the operating shaft.

The feed end of the operating shaft 15 carries a corrugated annular material-rotating device 24 mounted through a set of spider arms 25 on a sleeve 26 carried on the end of the shaft 15. The function of the device 24 is to produce a rotating movement of the mass of material adjacent the end plate 27 and the discharge slit. Immediately in front of the annular member 24 is mounted an end plate 27 which is held in place against the end of the casing 10 by a locking ring 28 having screw threaded relation with the casing at the forward end thereof. A pin 29 extending from the end of the casing 10 cooperates with a notch 30 formed in the edge of the end plate 27 to prevent the plate from rotating in its seat.

The end plate 27 is provided with a discharge slit 31 extending in a vertical disposition near the lower portion of the plate. The slit is provided at its inner edge with a knife-edge flange 32 which serves to cut a shaving from the rotating mass of material passing thereby and to direct the shaving of material into and through the discharge slit 31. The length of the discharge slit 31 may be varied by a slidible gate member 33 whose position may be adjusted vertically through the engagement therewith of a screw 34 having a knurled head 35 and coacting with a fixed bracket 36 mounted on the end plate. It will be seen that rotation of the knurled head 35 raises and lowers the slidible gate member 33 to thereby vary the extent of opening of the discharge slit 31.

The rotation of the operating shaft 15 produces a forward movement of the material in the casing 10 through the screw action developed by the helically positioned material-moving blades 16. The material which is thus pushed forward into engagement with the forward end plate 27 is caused to rotate by the action of the corrugated annular member 24 which rotates in close engagement with the end plate 27. The rotative movement which is given the material in contact with the plate 37 produces a discharging operation of material through the slit 31 since the inwardly extending knife-edge 32 formed at the inner edge of the slit 31 serves to cut a shaving of material from the mass and direct it into and through the adjacent discharge slit.

It will be seen that the material-moving action of the blades 16 will feed material toward the discharge end of the casing 10 at a faster rate than it can be discharged through the relatively minute discharge slit 31. The result of this is the accumulation of material under pressure at the discharge end of the casing. In order to limit the pressure thus produced to a predetermined maximum degree, the blades 16 are arranged to yield when the desired pressure has been reached and to take positions lying in planes perpendicular to the axis of rotation of the shaft whereupon the forward movement of the material longitudinally of the casing is suspended, while a constant spring pressure against the mass of material is maintained. When the resisting pressure is again reduced by the discharge of material through the orifice 31, the spring action of the blades again moves them to helical positions in which movement of the material is resumed. By this arrangement a constant pressure is maintained in the material at the discharge end of the casing with the result that an unvarying rate of feed of material through the discharge slit takes place.

The journaling of the operating shaft 15 in the elongated bearing member 14 does away with the necessity of a bearing support for the forward end of the shaft so that the end plate 27 can be readily removed at any time by the simple preliminary removal of the locking ring 28. This provides access to the interior of the casing 10 for any purpose.

What I claim is:—

1. In a device for feeding finely divided material, a casing provided with a discharge port of restricted size, a rotatable shaft within the casing, arms rigidly secured to said shaft, a helical spring blade secured at one end to each arm for moving material toward the discharge port at a rate faster than the material can be discharged through the port, the free end of said spring blades adapted to yield when a predetermined maximum pressure has been reached in the mass of material adjacent the discharge port.

2. In a device for feeding finely divided material, a casing provided with a discharge opening, a rotatable shaft in the casing, a series of radially disclosed arms carried by the shaft, a helically disposed material-moving blade secured at one end to each of said arms to deliver material to the discharge port at a faster rate than it can be discharged therethrough, and the free end of said blades being arranged to swing to an inoperative position when the resisting pressure has reached a predetermined maximum.

3. In a device for feeding finely divided material, a casing provided with a discharge opening of restricted size, a rotatable shaft in the casing, helically disposed material-

moving blades carried by the shaft, said blades being formed of spring material and supported only at their forward ends, said blades being arranged to deliver material to the discharge port at a faster rate than the material can be discharged through the port, and the free end of said spring blades adapted to move into alignment with the forward end thereof when the resisting pressure has reached a predetermined maximum and to exert a constant spring action against the material to maintain a uniform pressure therein.

4. In a device for feeding finely divided material, a casing provided at one end with a closure plate having a radially extending discharge slit therein, a knife-edge flange extending inwardly from the edge of the slit in position to divert material through the slit, a rotatable shaft in the casing, helically disposed material-moving blades secured at one end to said shaft, said blades being formed of spring material and the free end thereof adapted to swing to inoperative position when the material fed to the vicinity of the discharge opening has reached a predetermined maximum pressure.

5. In a device for feeding finely divided material, a casing provided at one end with a closure plate having a radially extending discharge slit therein, a gate member for varying the length of the slit, a knife-edge flange extending inwardly from an edge of the slit in position to divert material through the slit, a rotatable shaft in the casing, helically disposed blades having one of their ends rigidly secured to the shaft for moving material toward the discharge slit at a rate faster than the material can pass through the slit, and said blades being adapted to swing to inoperative position when the pressure of the material in the casing adjacent the discharge slit has reached a predetermined maximum, said blades exerting

a constant tension on the material to maintain a uniform pressure therein. 45

6. In a device for feeding finely divided material, a casing provided at one end with a closure plate having a radially extending discharge slit therein, a knife-edge flange extending inwardly from the edge of the slit in position to divert material through the slit, a rotatable shaft in the casing, helically disposed blades carried by the shaft to move the engaged material toward the closure plate, the free edge of said blades being adapted to swing to an ineffective position within the material when a predetermined maximum pressure has been reached in the material adjacent the discharge opening, 60 and peripherally corrugated means carried by the shaft for rotating the mass of material adjacent the closure plate to cause a ribbon of material to be cut from the mass by the knife-edge flange and diverted 65 through the discharge slit.

7. In a device for feeding finely divided material, a casing provided at one end with a closure plate having a radially extending discharge slit therein, a knife-edge flange 70 extending inwardly from the edge of the slit in position to divert material through the slit, a rotatable shaft in the casing, means carried by the shaft for advancing material toward the closure plate, means 75 carried by the shaft and spaced radially therefrom for rotating the mass of material adjacent the plate to thereby cause the knife-edge flange to cut a ribbon of material from the mass and divert it through the slit, a supply hopper on the other end of the casing, and means separate and apart from said blades operated by the shaft for agitating material in the supply hopper.

Witness my hand this 26th day of September, 1924, at the city of Salina, in the county of Saline, and State of Kansas. 85
